United States Patent Office

Des. 202,225
Patented Sept. 7, 1965

202,225

PACKAGING CONTAINER FOR FOOD OR THE LIKE

Henry H. Huston, Huntington, N.Y., assignor to Lily-Tulip Cup Corporation, New York, N.Y., a corporation of Delaware

Filed Dec. 11, 1964, Ser. No. 82,995

Term of patent 14 years

(Cl. D58—17)

FIG. 1 is a top plan view of a packaging container for food or the like, embodying my new design;

FIG. 2 is a side elevational view; and

FIG. 3 is a bottom plan view thereof.

I claim:

The ornamental design for a packaging container for food or the like, substantially as shown.
